UNITED STATES PATENT OFFICE.

BRUNO BEAUPRE, OF ST. PAUL, AND JOHN C. MELOY, OF HASTINGS, MINN.

AMALGAMATOR.

SPECIFICATION forming part of Letters Patent No. 339,842, dated April 13, 1886.

Application filed November 17, 1885. Serial No. 183,117. (No model.)

To all whom it may concern:

Be it known that we, BRUNO BEAUPRE, residing at St. Paul, county of Ramsey, State of Minnesota, and JOHN C. MELOY, residing at Hastings, in the county of Dakota and State of Minnesota, citizens of the United States, have invented certain new and useful Improvements in Ore-Amalgamators; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical section. Fig. 2 is a sectional detail. Fig. 3 is a cross-section.

This invention relates to improvements in amalgamating apparatus for separating gold and silver from their ores, its object being to pass the pulped ore up through a body of mercury by means of hydrostatic pressure, so as to bring the two into very intimate relations and entirely amalgamate the metal in the pulp; and it consists in the construction and novel arrangement of parts, as will be hereinafter fully described, and pointed out in the claims.

Referring to the accompanying drawings by letter, A designates a vessel to receive the ore, pulped in the usual manner so that it will flow. If desired, the vessel A may be provided with a pulp-agitator, A', consisting of a vertical shaft having a bearing in the top of the vessel A, with an agitator-blade on its lower end and a pulley on its upper end, driven by a belt from any proper source of power. The lower part, a, of the vessel A is funnel-shaped, to assist the pulp to flow into the pipe B, which descends from the lowest point of said vessel. The pipe B runs vertically downward far enough to give the descending pulp a sufficient amount of pressure to accomplish its purposes. b is a valve at a proper point on the descending part of the pipe B, to cut off the descent of the pulp when desired. The said pipe at its lowest point curves into a horizontal position, having upon it a valve, b', on its horizontal part. It then bends upward to enter the central point of the bottom of the amalgamating-chamber C, which

is a vertical cylindrical drum having its bottom cone-shaped, with the pipe B opening at c into the apex thereof.

c' is an outlet-valve a suitable distance below the top of the amalgamating-chamber, and adapted to draw off the exhausted pulp.

D is a mercury-chamber standing vertically by the side of the vertical portion of the pipe B, and having its lower end communicating therewith through a pipe, d, at a point below the valve b. The said pipe is controlled by the valve d', as shown.

E E are guide-plates for the material passing through the amalgamating-chamber, each of which is shaped like the inverted frustum of a cone, and has its outer edge secured to the interior of the amalgamating-chamber, and a central opening at its center.

F is a rod passing vertically down through the center of the top of the amalgamating-chamber, with its upper end threaded and carrying the nut f, by means of which the rod is made vertically adjustable within the chamber. The rod F passes through a packing-box 75 or an air-tight opening in the top of the amalgamating-chamber, so that the air-cushion in said chamber may act perfectly.

G G are circular guide pieces, convex on the upper surfaces and having annular grooves 80 g on their lower surfaces. One of these pieces is secured on the end of the rod F, and the other is secured on the rod between the guide-plates E, the rod F passing through the central opening of said plates. As many guide- 85 plates E and guide-pieces G may be used as are desirable.

H is a casing inclosing the lower part or all of the vessel A, all of the pipe B, and the lower part or all of the amalgamating-chamber. The said casing forms a steam-jacket around the part it incloses, steam being admitted either through the tube h or h', to heat the pulp or mercury in the apparatus, with one or more pipes, h'', for the discharge of the 95 steam into the ore pulp near the bottom of the vessel A.

I is a device in the shape of the frustum of a cone and secured within the amalgamating-chamber over the opening c of the pipe B. 100 The said device is open at the top, and is provided with the perforations i near its lower

edge, in order to allow the amalgam to be drawn off.

- J is a circular frame of suitable depth, within and across which are fastened metallic straps 5 j, with their edges vertical and crossing each other at right angles, so as to form the rectangular channels j' between them, and having the same depth as the frame. These channels have sufficient length to change the pulp 10 coming from the pulp-pipe from a lateral to a vertical direction, so that the pulp passes vertically into the amalgamating-chamber. The frame J is placed either immediately above the opening of the pulp-pipe or with its lower 15 end reduced in size and inserted in said opening, as shown. b' is a valve or faucet opening from the amalgamating-chamber just above its lower conical end, and is used to draw off the amalgam formed above it.
- 20 The manner of using the apparatus is as follows: The valves b, b', and c' are closed. The valve d' is then opened until the mercury fills the amalgamating-chamber and the pipe B up to said valve d', when it is closed and the 25 valves b and c' are opened. The pulp then descends and the pressure, because of the height of the pipe B, forces it through the mercury in the pipe B and in the amalgamating-chamber, bringing it into very intimate 30 relation therewith, so as to cause all particles of metal to amalgamate. The pulp, passing from the pulp-pipe through the channels j' in the frame J, is separated into smaller streams and divided up, and the flow of the same is changed 35 thereby from a lateral to a vertical direction, as hereinbefore explained. The device I directs the pulp up against the lower surface of the lower guide-piece G, which deflects it outward to the side of the amalgamating-chamber, and 40 it is again deflected inward by the under surface of the lower guide-plate E, and so on, so that it is made to follow a sinuous course through the mercury before it rises above it. The said guide-pieces and guide-plates also 45 prevent the mercury from rising suddenly when the exhausted pulp flows off through the valve c'. The purpose of the valve c' is to allow a continuous flow of the exhausted pulp when the machine is in operation. The air- 50 cushion formed by the rising of the pulp above the valve c' and the opening of the said valve to a greater or less extent control and regulate the working of the machine, the flow of the pulp, and the pressure in the pulp-pipe B.
- 55 If it is desired to pass a large quantity of pulp through the machine in a given time, the valve c' is thrown more widely open than in passing a small quantity therethrough. The valve c' is kept open to a greater or less extent all the while the machine is in operation, except when the amalgam is drawn off. The pulp cannot rise much above said valve, because the air-cushion is formed in the top of the amalgamating-chamber, which air-cushion 60 also prevents shock in working the apparatus.

The specific gravity of mercury being less than

gold and greater than silver, the silver amalgam rises to the top of the mercury in the amalgamating-chamber, and when the valves b c' 70 are closed and the valves b' d' are opened the silver amalgam will be forced out of the valve b' by the pressure of the mercury in the mercury-chamber D. As soon as all the said amalgam has been pressed out, the valves d' 75 b' are closed, to prevent the free mercury from escaping. The valves b c' are then opened and the operation continued. The gold amalgam, being heavier than the mercury, is at the bottom of the same, and is drawn off through the valve b'. If the amalgam consists of silver, gold, and mercury, it is drawn off either at the valve b' or the valve b', according to its specific gravity. The perforations i of the device I preventing a pocket being formed 80 outside of said device, the pulp in its descent not only forces itself, when exhausted, out of the valve c', but forces the mercury largely into the amalgamating-chamber also, where the most of the process takes place.

If desired, the valve c', instead of being a discharge-valve, may be on a vertical pipe leading to a machine identical with the one above described, so that if any metal remains in the pulp after the first process it may be repeated. The second apparatus is on a lower level than the first, to increase the pressure.

The heating of the pulp and mercury in the pipe B and the vessel A and the amalgamating-chamber by means of the steam-jacket 100 H and the discharge of the steam through the pipes h' h into the pulp in the vessel A, as shown, greatly facilitates the process of amalgamating the metals in the pulp, it being well known that heat causes metals to amalgamate more freely.

We are aware of Patent No. 260,389, and therefore do not claim any of the devices shown therein, when broadly considered.

Having thus described this invention, what we claim, and desire to secure by Letters Patent, is—

1. The combination of the amalgamating-chamber having a discharge-valve near its top, the pulp-pipe discharging into the bottom of the said chamber and provided with a valve to stop the flow of pulp on its vertical part, and an amalgam-discharge valve on its horizontal part, and the mercury-chamber discharging from its lower end by a valve-controlled pipe, with the pulp-pipe just below the valve on its vertical part, substantially as specified.

2. The combination of the pulp-pipe and the amalgamating-chamber having a conical bottom with the device I, secured over the entrance of the pulp-pipe into the chamber, the guide-plates E, and the guide-pieces G, substantially as specified.

3. The combination of the pulp-pipe B, provided with the valves b b', and having a pulp-vessel on its upper end, the amalgamating-chamber C, having a conical bottom and provided with the discharge-valve c' near its

upper end, the mercury-chamber D, communicating with the pipe B below the valve b by means of the valve-controlled pipe d, the device I, provided with the perforations i, the guide-plates E, and the guide-pieces G, substantially as specified.

5. The combination, with the pulp-pipe and amalgamating-chamber, of the frame J, having the cross-pieces j, forming between them the vertical channels j', substantially as specified.

In testimony whereof we affix our signatures 20 in presence of two witnesses.

BRUNO BEAUPRE.
JOHN C. MELOY.
